UNITED STATES PATENT OFFICE.

CARL MARTIN, OF MAGDEBURG-BUCKAU, GERMANY, ASSIGNOR, BY MESNE ASSIGNMENTS, TO THE FRIED. KRUPP GRUSONWERK, OF SAME PLACE.

GUN-MOUNTING.

SPECIFICATION forming part of Letters Patent No. 601,154, dated March 22, 1898.

Application filed June 30, 1892. Serial No. 438,575. (No model.) Patented in Germany January 28, 1892, No. 65,553; in Belgium March 17, 1892, No. 98,837; in France March 22, 1892, No. 220,323; in Switzerland May 7, 1892, No. 5,088; in England May 11, 1892, No. 8,954; in Sweden May 21, 1892, No. 4,234; in Spain June 11, 1892, No. 13,325; in Italy June 30, 1892, XXVI, 32,029; in Austria-Hungary June 21, 1893, No. 43/1,839 and No. 27/1,877, and in Denmark June 25, 1893, No. 127.

To all whom it may concern:

Be it known that I, CARL MARTIN, a subject of the Emperor of Germany, and a resident of Magdeburg-Buckau, in the Kingdom 5 of Prussia, Germany, have invented certain new and useful Improvements in Gun-Mountings, (for which I have obtained Letters Patent in other countries, as follows: Germany, January 28, 1892, No. 65,553; Belgium, March

- 10 17, 1892, No. 98,837; France, March 22, 1892, No. 220,323; Switzerland, May 7, 1892, No. 5,088; England, May 11, 1892, No. 8,954; Sweden, May 21, 1892, No. 4,234; Spain, June 11, 1892, No. 13,325; Italy, June 30, 1892, XXVI, 15 No. 32,029; Austria-Hungary, June 21, 1893, No. 43/1,839 and No. 27/1,877, and Denmark, June 25, 1893, No. 127,) of which the following is a specification.

My invention relates to improvements in 20 rotatable cupolas, turrets, or other rotatable mountings for ordnance.

The object of my said invention is to increase the stability of armor-plated pivotal turrets or cupolas or other rotatable mountings of the kind in which the training of the 25 gun is effected by turning the mounting upon a central pivot without diminishing the easy mobility by which mountings of this class are distinguished from those arranged to move 30 upon a roller-path.

According to this invention I use in lieu of the single central pivot heretofore employed two such pivots, each of which has its separate function.

In certain arrangements hitherto employed the turning movement of a cupola or turret, for example, took place upon a flat bearing fixed to the armored dome, which enabled the said dome to tilt upon the same so as to bear 35 against the glacis when the gun was fired and to assume directly afterward an upright position upon the said bearing after the absorption of the recoil. This arrangement rendered the successful design of the turret or 40 cupola a matter of considerable difficulty, for the center of gravity of the system had to be 45 vertically above the pivot. Moreover, for a

gun of great weight a pivot of a very large diameter was necessitated, whereby the friction during the turning of the dome became 50 considerable, so that the system would have no advantage over a mounting provided with a roller-path. This defect is obviated by the present invention, inasmuch as it distributes 55 the functions of tilting and turning between two pivots.

In order that my said invention may be clearly understood, I will now proceed to describe the same with reference to the accompanying drawings, in which— 60

Figure I is a vertical central section of an improved cupola constructed according to my invention, including a detail plan view of the toothed wheel and pinion. Fig. II is a vertical central section of an alternative form 65 of cupola also constructed according to my invention. Fig. III is an elevation at right angles to Fig. II of the brake mechanism shown in that figure. Fig. IV is a vertical central section of an alternative form of the tilting- 70 pivot shown in Fig. II. Fig. V is a plan view of a portion of Fig. IV and is hereinafter more particularly described.

Like letters of reference indicate corresponding parts in all the figures. 75

In Fig. I the column A rests at its lower end upon one arm of the lever B, from the other arm of which the counterweights C are suspended.

D is the armor-dome, which when the counterweight is in its highest position bears upon the glacis E, whereas when the said counterweight occupies its lowest position, as shown in the drawings, the dome rises from the glacis and the embrasure F is revealed, so 80 that the gun G can be run out.

H is a hand-wheel, which by means of bevel-wheels H' and a vertical shaft J and the pinion J', secured to the lower end of the said shaft, has working connection with a toothed 85 wheel L, secured to the upper end of the column A, which is so arranged that it cannot 90 turn.

M is a pivot, the base O of which in the

present example is circular, but which may be of any other suitable shape, and is of considerably greater diameter than the body M. The said base is supported upon the head of the column A and prevented from turning by the feather P, which enters a recess in the base O of the pivot M, and a similar recess in the head of the column A. When the gun is fired, the cupola tilts upon the rear edge 10 a of the base O, and the latter rises a little from the feather P, but is compelled by gravity when the gun-carriage assumes the upright position to move the said mounting back again exactly to its former position. If 15 the cupola is struck by a projectile, it tilts in a similar manner.

The rotation of the cupola takes place upon the upper plane surface of the pivot M. The said pivot prior to the firing is rigidly locked 20 to the rotary portion K of the turret and the dome D by means of a brake-lever N, carried by the turret and operating a suitable brake, which bears upon the pin M.

In Fig. II, to which, with Figs. III, IV, and 25 V, reference will now be made, a cupola is shown in which the embrasure is always uncovered, and accordingly the dome D need only be raised when the gun is to be traversed, and then only to such an extent that its bevelled edge will no longer touch the glacis E. In this example when the gun is fired or when 30 a shot hits the cupola the part K of the carriage tilts around the edge of the pivot M, and the feather P insures its return movement to its original position. The turning-pivot M is at the lower end of the column A, which in this case is arranged to rotate and turns in the footstep b. The raising and lowering 35 of the gun-carriage and dome is effected by raising and lowering the pivot O, which for this purpose is screw-threaded to engage with the upper end of the spindle A, which also is screw-threaded, as shown.

Q is a cone, the upper end of which carries 40 a disk Q'.

R is a brake-band, the ends of which are connected by a spindle N, provided with right-hand and left-hand threads and with a lever N'. Between the said ends of the band R the 45 forked end of an arm S, extending from the pivot M, embraces loosely the spindle N in such a manner that the said arm may slip vertically over the spindle when the pivot M is raised or lowered. The brake is applied to 50 grip the said disk by turning the lever N'. The rotary column A is provided with a bevel-wheel L, which can be turned by the hand-wheel H by means of intermediary shafting and toothed wheels.

55 When the brake-band is tightened, the pivot M may be raised or lowered but cannot be turned, and when the brake-band is slackened after the dome is sufficiently raised, the pivot may be turned but cannot longer be 60 raised or lowered, as is hereinafter more fully explained. This arrangement permits the

operating mechanism to be very much simplified and the working of the gun greatly facilitated, as the raising, lowering, and turning of the mounting can all be effected by means of a very simple operation, which will now be described.

Supposing the brake-band R is released, if the dome D bears firmly upon the glacis E, a turning movement of the column A in the 75 direction of the arrow, Fig. II, will not be possible, because the friction between the dome and the glacis is too great to permit the rotation of the carriage K, while the latter in turn prevents by the feather P the turning of the 80 pivot M. This pivot would, however, allow the column to turn in the direction of the arrow if the said pivot M could descend, which is prevented by the arm S bearing upon the top of the disk Q'. If, on the other hand, the 85 column A is turned in the opposite direction by means of the hand-wheel H, the gun-carriage K is not at first rotated because the dome bears upon the glacis, as aforesaid, and therefore the pivot M is screwed upward by 90 the turning of the column A, but as soon as the pivot M, by lifting the carriage K and the dome D, raises the edge of the latter off the glacis the spindle A and the carriage and dome will all turn together. At this moment 95 the turning movement of the hand-wheel H may also be changed, and a turning movement of the gun-carriage to the right may take place. If the dome is required to be lowered again, it is only necessary to prevent 100 the gun-carriage from rotating by operating the brake-lever N' and to turn the column A again in the direction of the arrow, Fig. II, by means of the hand-wheel H, whereupon the said column screws the pivot M downward 105 until the dome D rests tightly upon the glacis.

The advantages of this arrangement are as follows: One and the same device is used for raising and lowering the cupola and traversing the gun, and, further, hitherto in the majority of cases with separate devices for the raising and lowering and for the turning of the cupola, there was no measure or indication afforded as to how high the armor-plate cover had to be raised in order to enable rotation of the cupola or turret to be effected, and therefore it was generally raised too high, whereas in the improved arrangement herein described this is now regulated automatically as set forth. This advantage results 110 from the separation of the turning-pivot from the other pivot about which the tilting occurs.

The principal advantages of the use of separate pivots are, as hereinbefore stated, that the pivot about which the tilting occurs may 115 be made of any desired diameter without diminishing the ease with which the cupola, turret, or other mounting may be rotated, and that the gun-carriage is compelled by the feather P, which forms a guide, to return 120 each time exactly to its former position. This latter is a very important advantage, as in

former armor-plated gun-carriages with a combined turning and tilting pivot there existed always the tendency to alter the horizontal direction of the gun during firing or during the return of the gun to its position of equilibrium.

The hereinbefore-described examples have shown the application of the invention to cupolas in which the gun has no recoil in the carriage. If, however, it is preferred to allow the gun a slight recoil in the gun-carriage in order to put the material under as little stress as possible, the application of the invention would be the same, but the amount of the tilting would be diminished.

Having now particularly described and ascertained the nature of this invention and in what manner the same is to be performed, I declare that what I claim is—

1. In heavy ordnance the combination substantially as set forth, of the gun, the central turning-pivot upon which the gun is mounted for training, and the separately-located additional rocking bearing upon which the gun 25 tilts when it is fired or a shot hits the cupola, as explained.

2. In heavy ordnance, the combination of the gun and the vertical central support, upon which the gun is mounted, formed with two 30 separate bearings which respectively permit the turning of the gun for training and the tilting of the cupola, said tilting-bearing being provided with a guide which insures the return of the gun to the same position substantially as set forth.

3. In heavy ordnance, the combination of the gun, the vertical central support upon which the gun is mounted, provided with a turning-pivot for training and a separate 40 rocking bearing, and means for rotating the gun, working connections with said means for effecting the raising or lowering as well as the training substantially as set forth.

4. In heavy ordnance, a mounting in combination with a turning-pivot arranged to turn in a bearing and upon which the mounting rests and adapted to rock, and a feather P interposed between the mounting and its pivot and embedded in said parts so as to 50 prevent relative turning while permitting the rocking movement as explained.

5. In heavy ordnance, the combination of the gun, the central vertical support upon which the gun is mounted, formed with the 55 training-bearing and the tilting-bearing, the brake, for locking the fixed and rotatable parts of the support against relative movement, said brake being carried by one of said parts and having a controlling-lever for forcing it into contact with the other, and means

for moving the gun on its training-bearing, all substantially as set forth.

6. In heavy ordnance, the combination of the cupola, the gun, the central vertical support for the cupola and gun formed in two 65 parts screw-threaded together and also with a training-bearing and a tilting-bearing, the means for rotating the gun on its training-bearing and the brake for locking one of the screw-threaded parts, while the other rotates in order to change the length of the central support and raise or lower the cupola, all substantially as set forth.

7. In a gun-mounting the combination of the glacis, the cupola formed to seat upon the 75 glacis, the gun beneath the cupola, the central vertical support for the gun and cupola, formed in two parts, screw-threaded together, and with a training-bearing, and means substantially as described for rotating the lower 80 part of the central support in either direction, as and for the purpose explained.

8. In a gun-mounting, the combination of the gun, the central vertical support, upon which the gun is mounted, formed in two 85 parts and screw-threaded together, and having a turning-bearing on the lower part, the driving connection for rotating the lower part, the arm on the upper part provided with a 90 brake and the fixed part of the structure co-operating with the brake, all substantially as and for the purpose set forth.

9. In a gun-mounting the combination of the glacis, the cupola constructed to seat on the glacis, the gun and the central vertical 95 support carrying the gun and adapted to lift the cupola; said support being formed in two parts screw-threaded together, of which the upper one is formed with a rocking bearing for the gun and a brake for controlling rotary movement, and the lower one is formed with a rotating or training bearing and means for rotating the said lower part; all substantially as set forth and for the purpose specified.

10. In a gun-mounting, the combination of the central vertical support, formed in two parts screw-threaded together, a rotating bearing and rotating connections for the lower part, a bearing for the upper part provided with a surrounding disk, an arm on said upper part, a band-brake surrounding the disk and connected with said arm and a controlling-lever for regulating the tension on said band-brake, all substantially as and for the 115 purpose set forth.

CARL MARTIN.
